PLAYGROUND ROUNDABOUT

Robert S. Wormser, Hillsdale, Mich., assignor to Game Time, Inc., Litchfield, Mich.

Filed Mar. 19, 1970, Ser. No. 21,981

Term of patent 14 years

Int. Cl. D21—03

U.S. Cl. D34—5

FIG. 1

FIG. 3

FIG. 1 is a perspective view of a playground roundabout showing my new design.

FIG. 2 is a top plan view, and

FIG. 3 is a side elevation view of FIG. 2.

I claim:

The ornamental design for a playground roundabout, substantially as shown and described.
